UNITED STATES PATENT OFFICE.

PAUL MACGAHAN, OF PITTSBURGH, PENNSYLVANIA, ASSIGNOR TO WESTINGHOUSE ELECTRIC AND MANUFACTURING COMPANY, A CORPORATION OF PENNSYLVANIA.

ARC-EXTINGUISHING DEVICE.

1,308,365.

Specification of Letters Patent.

Patented July 1, 1919.

Application filed August 10, 1916. Serial No. 114,162.

To all whom it may concern:

Be it known that I, PAUL MACGAHAN, a citizen of the United States, and a resident of Pittsburgh, in the county of Allegheny and State of Pennsylvania, have invented a new and useful Improvement in Arc-Extinguishing Devices, of which the following is a specification.

My invention relates to electrical systems of distribution and particularly to apparatus for extinguishing arcs that occur in such systems without disturbing the operation of the apparatus connected thereto.

One object of my invention is to provide a device of the above indicated character that shall alternately open and close a circuit interrupter to so reduce the voltage of the circuit that the arc will be extinguished without causing the apparatus connected to the circuit to fall out of synchronism.

Another object of my invention is to provide a device of the above indicated character that shall have a time-limit overload relay for precluding the automatic reclosing of the interrupter after the arc has persisted for such predetermined periods of time as shall be determined by the time setting of the overload relay.

Copending application Serial No. 83,786, filed March 13, 1916 by F. E. Ricketts and assigned to the Westinghouse Electric and Manufacturing Company discloses a device for alternately opening and closing a circuit interrupter in accordance with the difference in potential on the respective sides of the interrupter and means for precluding the closing of the interrupter after the arc has existed for a predetermined period of time.

In my invention, I provide an overload relay for tripping the interrupter, a no-voltage relay for quickly reclosing it and a time-limit overload relay for precluding the operation of the reclosing means after the arc has existed for a predetermined period of time.

The single figure of the accompanying drawing is a diagrammatic view of a distributing system that is provided with an arc-extinguishing means embodying my invention.

A generator 1 supplies energy to conductors 2 and 3 of a distributing system or circuit 4 that is provided with an interrupter

5 which is adapted to be tripped when an overload or an arcing ground occurs upon the circuit 4 and to be immediately reclosed in order that the load which is connected to the circuit will not fall out of synchronism. That is, if the circuit interrupter 5 is tripped, the voltage upon the load end of the circuit 4 is reduced substantially to zero, and, if the overload is caused by an arcing ground, the arc will be extinguished because of the lack of voltage to maintain it.

The circuit interrupter 5 is provided with a tripping electromagnet 6 and a closing electromagnet 7. A series transformer 8 is operatively connected to the circuit 4 and is adapted to energize the windings 9 and 10 of overload relays 11 and 12. The overload relay 11 is adapted to operate substantially instantaneously, upon the occurrence of an overload, for the purpose of completing a circuit from one conductor 13 of a circuit 14, comprising a source 15 of electromotive force, through the tripping electromagnet 6 to the other conductor 16 of the circuit 14. Thus, when an overload occurs upon the circuit 4, the interrupter 5 will be tripped.

A no-voltage relay 17 is adapted to be connected across the conductors 2 and 3 on the load side of the interrupter 5 and comprises a winding 18, a movable core member 19, a bridging contact member 20 and stationary contact members 21. One of the stationary contact members 21 is connected to the conductor 13 and the other stationary contact member 21 is connected to one of the stationary contact members 22 of a relay 23. The other stationary contact member 22 of the relay 23 is operatively connected to the movable contact member 24 of a switch 25 and to the stationary contact member 26 of a time-limit relay 27. The other stationary contact member 26 of the relay 27 is connected to one terminal of its winding 28, the other terminal of which is connected to one terminal of the electromagnet 7. The other terminal of the electromagnet 7 is connected to the conductor 16 of the circuit 14.

Thus, when the circuit interrupter 5 is tripped, the voltage of the load end of the circuit 4 will drop substantially to zero, and the movable core member 19 of the relay 17 will move downwardly to cause its bridging contact member 20 to engage its stationary contact members 21, thereby completing the circuit

through the electromagnet 7 for the purpose of reclosing the interrupter 5.

The time-limit overload relay 12 comprises the winding 10, a dash pot or other suitable 5 time-element device 29, a movable bridging contact member 30, and stationary contact members 31. One of the stationary contact members 31 is operatively connected to the conductor 13 and the other stationary contact member 31 is operatively connected to one terminal of the winding 32 of the relay 23, the other terminal of which is operatively connected to the conductor 16 of the circuit 14.

15 The relay 23 is provided with a latching device 33 for the purpose of latching its movable core member 34 in such position, after the winding 32 is energized, that its movable contact member 35 is held out of 20 engagement with its stationary contact members 22. Thus, when the relay 12 operates, it so energizes the relay 23 that a drop of voltage in the circuit 4 will not cause the electromagnet 7 to be actuated. In other 25 words, the relay 23 is adapted to be energized if the overload has existed upon the circuit 4 for a predetermined period of time. The dash pot 29 of the relay 12 is, of course, so set that the circuit interrupter 5 may be 30 tripped and reclosed a predetermined number of times before the contact member 30 engages the contact members 31. Consequently, the time setting of the relay 12 is dependent upon the time required to extinguish an arc by successively reducing the voltage thereacross.

The relay 27 is provided for the purpose of precluding the continued energization of the winding of the electromagnet 7 should 40 the voltage of the generator 1 fail, for any reason. That is, if the voltage of the generator 1 fails, the movable contact member 20 of the relay 17 will engage its stationary contact members 21 and thus cause current 45 to traverse the electromagnet 7 until the voltage is again restored to the circuit 4. The relay 27 is provided with a dash pot 36 which is so set that, if current traverses its winding 28 for a predetermined relatively 50 short interval of time, its movable contact member 37 will be disengaged from its stationary contact members 26 and thus open the circuit of the electromagnet. The relay 27 may be provided with a latch 39 for holding it in its open position, after it has operated, until it is manually reset.

The movable contact member 24 of the switch 25 is adapted to engage a stationary contact member 38 that is operatively connected to the conductor 13 for the purpose of so energizing the electromagnet 7 that the circuit interrupter 5 may be non-automatically reclosed, under any condition.

When an overload traverses the circuit 4, 65 the relay 11 will operate to trip the inter-

rupter 5 through the electromagnet 6 and, at the same time, the relay 12 will start to operate. When the circuit interrupter 5 opens, the voltage on the load end of the circuit 4 will so decrease as to cause the core 70 member 19 of the relay 17 to move downwardly. This will cause the electromagnet 7 to reclose the interrupter 5. If the arc that causes the overload upon the circuit 4 has been extinguished by reason of the reducing of the voltage, nothing further will occur. However, if the arc persists, the relay 11 will again cause the interrupter to be tripped and, similarly, the relay 17 will again cause the interrupter to be reclosed. 75 After the tripping and reclosing operations have occurred a number of times, dependent upon the time-setting of the relay 12, the relay 22 will operate to thus prevent the automatic reclosing of the interrupter. 80

If the overload is caused by a permanent ground, the arc will not be extinguished, no matter how many times the interrupter is opened and closed. Hence, it has been found that, if the ground is not cleared after the 85 interrupter has opened and closed a relatively small number of times, it is useless to continue the operation, and, under such conditions, the latch 33 is adapted to so hold the relay 23 that the interrupter will not be 90 automatically reclosed until the latch 33 is manually released.

I do not limit my invention to the particular arrangement illustrated, as it may be variously modified within the spirit and 100 scope of the invention, as set forth in the appended claims.

I claim as my invention:

1. In an electric circuit, the combination with a circuit interrupter and means for 105 opening and closing the same, of an overload relay for controlling the opening of the interrupter when an overload occurs upon the circuit, a no-voltage relay for controlling the reclosing of the interrupter 110 when the voltage of the circuit is substantially zero, and a time-limit overload relay for opening the circuit of the reclosing means if the overload persists for a predetermined period of time.

2. In a system of distribution, the combination with a circuit interrupter, of means for alternately opening and closing the interrupter when a short circuit occurs on the system, and a time-limit overload relay for 115 rendering the closing means ineffective if the short circuit persists for a predetermined period of time.

3. In a system of distribution, the combination with a circuit interrupter, of means for opening the interrupter when an overload traverses the system, means for closing the interrupter as soon as the voltage on the system drops to a predetermined 125 value, and retarded overload-responsive 130

means for rendering the closing means ineffective if the overload persists for a predetermined period of time.

4. In a system of distribution, the combination with a circuit interrupter, of an overload relay for tripping the interrupter when an overload traverses the system, a no-voltage relay for closing the interrupter when the voltage on the system drops to a predetermined value, and a time-element overload relay for precluding the closing of the interrupter if the overload persists for a predetermined period of time.

5. In a system of distribution, the combination with a circuit interrupter and means for successively opening and closing the same when an overload traverses the system, of a time-element overload relay for precluding the reclosing of the interrupter after the overload has existed for a predetermined period of time.

6. In a system of distribution, the combination with a circuit interrupter and means for successively opening and closing the interrupter when an overload traverses the system, of retarded overload-responsive means for precluding the reclosing of the interrupter after the overload has existed for a predetermined period of time.

7. In a system of distribution, the combination with a circuit interrupter and means for successively opening and closing the interrupter when an overload traverses the system, of overload-responsive means for preventing the energization of the closing means of the circuit interrupter after the overload has existed for a predetermined period of time.

In testimony whereof, I have hereunto subscribed my name this 31st day of July, 1916.

PAUL MacGAHAN.
